Primary Examiner — Rebekah A Caruso(74) Attorney, Agent, or Firm — Rocklaw PLLC; Michael T. Fluhler(57) CLAIM

The ornamental design for a hair brush, as shown and described.

DESCRIPTION

FIG. 1 is a bottom view of a hair brush showing my new design;

FIG. 2 is a front axial view thereof;

FIG. 3 is a rear axial view thereof;

FIG. 4 is a right axial view thereof;

FIG. 5 is a left axial view thereof; and,

FIG. 6 is a top perspective view thereof.

The broken line showing in the accompanying drawings is for the purpose of illustrating environmental features and forms no part of the claimed design.
